(57) **CLAIM**

The ornamental design for a gasket for carbon fiber composite cable, as shown and described.

DESCRIPTION

FIG. 1 is a front, top and left side perspective view of a gasket for carbon fiber composite cable, showing our new design;
 FIG. 2 is a front view thereof;
 FIG. 3 is a rear view thereof;
 FIG. 4 is a left side view thereof;
 FIG. 5 is a right side view thereof;
 FIG. 6 is a top view thereof;
 FIG. 7 is a bottom view thereof;
 FIG. 8 is a front view of the half-body thereof;
 FIG. 9 is a rear view of the half-body thereof;
 FIG. 10 is a left side view of the half-body thereof;
 FIG. 11 is a right side view of the half-body thereof;
 FIG. 12 is a top view of the half-body thereof;
 FIG. 13 is a bottom view of the half-body thereof;
 FIG. 14 is a perspective view of the gasket for carbon fiber composite cable shown in an environment.
 FIG. 15 is an exploded perspective view of the gasket for carbon fiber composite cable shown in an environment.
 FIG. 16 is a front, top and left side perspective view of a second embodiment of a gasket for carbon fiber composite cable, showing our new design;
 FIG. 17 is a front view thereof;
 FIG. 18 is a rear view thereof;
 FIG. 19 is a left side view thereof;
 FIG. 20 is a right side view thereof;
 FIG. 21 is a top view thereof;
 FIG. 22 is a bottom view thereof;
 FIG. 23 is a front view of one third-body thereof;
 FIG. 24 is a rear view of one third-body thereof;
 FIG. 25 is a left side view of one third-body thereof;
 FIG. 26 is a right side view of one third-body thereof;
 FIG. 27 is a top view of one third-body thereof;
 FIG. 28 is a bottom view of one third-body thereof;
 FIG. 29 is a perspective view of the gasket for carbon fiber composite cable shown in an environment.
 FIG. 30 is an exploded perspective of the gasket for carbon fiber composite cable shown in an environment.
 FIG. 31 is a front, top and left side perspective view of a third embodiment of a gasket for carbon fiber composite cable, showing our new design;
 FIG. 32 is a front view thereof;
 FIG. 33 is a rear view thereof;
 FIG. 34 is a left side view thereof;
 FIG. 35 is a right side view thereof;
 FIG. 36 is a top view thereof;
 FIG. 37 is a bottom view thereof;
 FIG. 38 is a front view of one quarter-body thereof;
 FIG. 39 is a rear view of one quarter-body thereof;
 FIG. 40 is a left side view of one quarter-body thereof;
 FIG. 41 is a right side view of one quarter-body thereof;
 FIG. 42 is a top view of one quarter-body thereof;
 FIG. 43 is a bottom view of one quarter-body thereof;
 FIG. 44 is a perspective view of the gasket for carbon fiber composite cable shown in an environment.
 FIG. 45 is an exploded perspective view of the gasket for carbon fiber composite cable shown in an environment.
 FIG. 46 is a front, top and left side perspective view of a forth embodiment of a gasket for carbon fiber composite cable, showing our new design;
 FIG. 47 is a front view thereof;

FIG. 48 is a rear view thereof;
 FIG. 49 is a left side view thereof;
 FIG. 50 is a right side view thereof;
 FIG. 51 is a top view of thereof;
 FIG. 52 is a bottom view of thereof;
 FIG. 53 is a front view of the half-body thereof;
 FIG. 54 is a rear view of the half-body thereof;
 FIG. 55 is a left side view of the half-body thereof;
 FIG. 56 is a right side view of the half-body thereof;
 FIG. 57 is a top view of the half-body thereof;
 FIG. 58 is a bottom view of the half-body thereof;
 FIG. 59 is a perspective view of the gasket for carbon fiber composite cable shown in an environment.
 FIG. 60 is an exploded perspective view of the gasket for carbon fiber composite cable shown in an environment.
 FIG. 61 is a front, top and left side perspective view of a fifth embodiment of a gasket for carbon fiber composite cable, showing our new design;
 FIG. 62 is a front view thereof;
 FIG. 63 is a rear view thereof;
 FIG. 64 is a left side view thereof;
 FIG. 65 is a right side view thereof;
 FIG. 66 is a top view thereof;
 FIG. 67 is a bottom thereof;
 FIG. 68 is a front view of one third-body thereof;
 FIG. 69 is a rear view of one third-body thereof;
 FIG. 70 is a left side view of one third-body thereof;
 FIG. 71 is a right side view of one third-body thereof;
 FIG. 72 is a top view of one third-body thereof;
 FIG. 73 is a bottom view of one third-body thereof;
 FIG. 74 is a perspective view of the gasket for carbon fiber composite cable shown in an environment.
 FIG. 75 is an exploded perspective view of the gasket for carbon fiber composite cable shown in an environment.
 FIG. 76 is a front, top and left side perspective view of a sixth embodiment of a gasket for carbon fiber composite cable, showing our new design;
 FIG. 77 is a front view thereof;
 FIG. 78 is a rear view thereof;
 FIG. 79 is a left side view thereof;
 FIG. 80 is a right side view thereof;
 FIG. 81 is a top view thereof;
 FIG. 82 is a bottom view thereof;
 FIG. 83 is a front view of one quarter-body thereof;
 FIG. 84 is a rear view of one quarter-body thereof;
 FIG. 85 is a left side view of one quarter-body thereof;
 FIG. 86 is a right side view of one quarter-body thereof;
 FIG. 87 is a top view of one quarter-body thereof;
 FIG. 88 is a bottom view of one quarter-body thereof;
 FIG. 89 is a perspective view of the gasket for carbon fiber composite cable shown in an environment; and,
 FIG. 90 is an exploded perspective view of the gasket for carbon fiber composite cable shown in an environment.
 In FIGS. 14, 15, 29, 30, 44, 45, 59, 60, 74, 75, 89 and 90, the broken lines are for the purpose of illustrating environment only and form no part of the claimed design.
 The front view shows only a part of the design, which actually extends in horizontal directions.
